UNITED STATES PATENT OFFICE.

MEAD HEDGLON, OF SYRACUSE, NEW YORK.

FOLDING TABLE FOR IRONING MACHINES.

Application filed June 27, 1927. Serial No. 201,942.

This invention relates to improvements in tables for domestic ironing machines, and has for its object to provide a combined ironing machine support and lunch or work table, 5 which may be readily and quickly converted to either of said uses. A further object is to provide a foldable and extensible table, whose top comprises several sections, the said sections being hinged to a common rigid frame 10 which also supports the ironing machine, the central top member being swingable upwardly for enabling the machine to be disposed in the ironing position, the ironing machine being mounted upon a movable frame, which is 15 arranged to swing downwardly for stowing the machine between the ironing intervals within the enclosure effected by the folding of the table. And a further object is to provide novel and simple means for raising and lowering 20 the machine and its movable support, and for positively locking the said parts in the ironing position.

The various features and parts of the invention will be understood from the detailed 25 description which follows, and by reference to the accompanying drawings, in which— Figure 1 is a top plan view of the folded table, the top portions being broken away for showing the arrangement of certain parts. 30 Fig. 2 is a front side elevation; showing the central top member raised and the machine disposed above the plane of the permanent frame—the ironing position. Fig. 3 is an end elevation of the same, the full lines showing 35 the position of the parts during the ironing operations, the dotted lines indicating the inoperative positions of said parts. Fig. 4 is a similar elevation, with one of the aprons removed, the full lines showing the table extended 40 and the machine lowered to the inoperative position; the dotted lines showing the position of certain parts while the ironing is being done.

Fig. 5 is an end elevation of a modified 45 form of the invention, and

Fig. 6 is a detail view of a portion of the means for swingably mounting and latching the ironing machine carrying member.

In the drawings, 2 represents a horizontal 50 rectangular open frame, the latter being supported at its four corners by legs 3, which may be secured by any suitable means, as

screws 3'. At the opposite sides of the frame 2, swingable wings, as 4, are secured by hinge members 5 and 5', the members 5 being rigid 55 to the frame, and the members 5' being rigid to the wings 4. When the wings are lowered, as shown in Fig. 3, their top edges are preferably disposed in the plane of the top face of the frame, and when said wings are extended, as shown in Fig. 4, they are disposed entirely above said plane. The space between the extended wings is closed by a central top member 6, the said member being hinged at its rear edge by means of a similar 60 leaf 5", which forms a third member of the rear hinge. The several hinge leaves are each provided with a number of spaced loops, which interfit with the loops of the other leaves (see Figs. 1, 3 and 4), and all of said loops are held in alinement by common pintles, as 5'. The ends of the table are preferably partially closed by sheet metal or other aprons, as 7, which may be secured to the frame 2 and the legs 3, by screws 7'. 75

16 represents an open rectangular frame, preferably made of angle-iron, which is loosely disposed in the opening of the stationary frame 2, and in which is seated the base 10, the latter preferably being rigidly secured thereto, as by screws 10". The frame 16 is hinged near its forward edge, and at a point below the plane of frame 2, to the front legs 3, by hinge members 17, the ends 17' of which are mounted upon a square shaft or rod 17", the said shaft being journalled in said front legs, and said shaft and frame 16 being movable as one part. To the rear under face of frame 16 is secured brackets 18 having horizontal slots, in which a rod 18' plays, the ends of the said rod being fixed to sleeves 19, which are slidable on the rear ends of operating levers 20, the movements of the sleeves being regulated by pins 20' carried by the said levers and which play in slots 20". The 80 sleeves 19 are provided with hand-knobs 19', by which the levers are manipulated. The forward ends of the levers 20 are formed with heads 20", having square openings to receive the shaft 17". The downward swinging of 85 the levers 20, as from the full line position of Fig. 3 to the full line position of Fig. 4, and vice versa, lowers and raises the ironing machine. These movements of the levers 20 are 90

- preferably controlled by coinciding slots, as 7^a, that are formed in the aprons 7, as shown in Fig. 3. It is desirable to lock the ironing machine in the raised or ironing position for holding the machine rigid and against accidental gravitation, and for this purpose, the top ends of the slots 7^a are formed horizontal, as at 7^b, in Figs. 3 and 4, the portions 7^b coinciding with the slots of the brackets 18. 10 The locking of the machine and related parts is effected by the operator sliding the sleeves 19 axially on the levers 20, out of registry with the main slots 7^a, as shown in Fig. 3.

In Fig. 5 is shown a modification of the raising and lowering mechanism, in which the hinge 17^c that supports the frame 16 turns loosely on a round rod 17^d, and the tilting of the frame, for moving the machine towards and from the ironing position is effected by 15 a toggle mechanism comprising a long arm 21, which is pivoted to the underside of the frame 16, and a short arm 21', which is rigid to a shaft 22 journaled in the front legs 3. The shaft 22 is partially rotated by a hand-lever 23. The full and dotted lines in Fig. 20 show the operative and inoperative positions of the movable parts. The toggle members 21—21', when in the dotted positions of Fig. 5, are disposed slightly out of alinement 25 for effecting a dead center that prevents the gravitation of the frame 16. The latter position of the toggle is maintained by means of a stop pin 24. When the frame is swung downwardly by the manipulation of lever 30 23, as shown by the full lines in Fig. 5, the arm 21' engages a similar pin 24', which positively holds the parts in the lowered position. The toggle mechanism is preferably disposed between the front side legs, while the lever 35 23 is preferably disposed outside of the adjacent leg, as shown.

Having thus described my invention, what I claim, is:—

1. A table for ironing machines, comprising a stationary open frame, means for supporting said frame horizontally, a shaft journaled to and beneath one edge of said frame, a second frame adapted to carry an ironing machine, means for connecting the second frame with said shaft, said second frame adapted to be loosely disposed in the opening of the first frame when the ironing machine is in the operative position, a lever connected to the second frame and to said shaft for lowering and raising the second frame, said lever carrying a sleeve, and means carried by the second frame and operable by said sleeve for holding said frame in its uppermost position.
2. A table for supporting and housing an ironing machine, comprising a stationary open frame, legs for supporting said frame horizontally, a shaft supported by the legs at one side of the frame, a second frame loosely telescoping the first frame adapted

to carry an ironing machine, means connecting the second frame to said shaft, a rod mounted beneath the second frame and paralleling said shaft, a lever for rocking said shaft for swinging the ironing machine towards and away from the first frame, and means carried by said lever and engaging said rod for locking the second frame in the telescoped position.

3. An ironing machine table including a frame having an open top, an ironing machine carrying member hinged to the frame and receivable in the opening of the top, a lever pivoted to the frame, means to connect the lever to said member, a slotted part carried by the frame and having an offset portion, and means movably connected to the lever and engageable with said offset portion to latch the lever against swinging.

4. An ironing machine table including a frame having an opening in its top, an ironing machine carrying member receivable in said opening, a shaft carried by the frame, a second shaft, means to mount the second shaft for transverse sliding movement on the under side of said member, means to slidably connect the second shaft to the first shaft so as to support the member from the first shaft for swinging movement, and means carried by the frame to engage the second shaft in one position thereof and to hold same and thereby the member against swinging movement and which in a second position of the second shaft permits same and thereby the member to be swung.

5. In an ironing machine table, a frame having an opening, an ironing machine carrying member receivable in the opening, means to support the member from the frame for swinging movements, a shaft, means to slidably mount the shaft on the member, and means carried by the frame to engage the shaft in one position thereof so as to hold same and thereby the member against swinging and in a second position of the shaft to permit same and thereby the member to be swung.

6. In an ironing machine table, a frame having an opening, an ironing machine carrying member receivable in the opening, means to support the member from the frame for swinging movements, a shaft, means to slidably mount the shaft on the member, and means carried by the frame and disposed at each of the ends thereof to engage the respective end portions of the shaft in one position thereof so as to hold the shaft and thereby the member against swinging and in a second position of the shaft to permit same and thereby the member to be swung.

7. In an ironing machine table, a frame having an opening, an ironing machine carrying member receivable in the opening, means to support the member from the frame for swinging movement, a shaft, means to slidably mount the shaft on the member, and

means carried by the frame and disposed at each of the ends thereof to engage the respective end portions of the shaft in one position thereof so as to hold the shaft and thereby ⁵ the member against swinging and in a second position of the shaft to permit same and thereby the member to be swung, said means at the frame ends including curved guides engaging the shaft ends to allow of swinging thereof, the guides having offset portions ¹⁰ to engage and hold the shaft against swinging and the member in operative position.

In testimony whereof I affix my signature.

MEAD HEDGLON.
